UNITED STATES PATENT OFFICE

110,529

DESIGN FOR A DIAL PLATE

Marcus H. Rhodes, Hartford, Conn.

Application March 3, 1938, Serial No. 75,549

Term of patent 3½ years

To all whom it may concern:

Be it known that I, Marcus H. Rhodes, a citizen of the United States and a resident of Hartford, in the county of Hartford and State of Connecticut, have invented a new, original, and ornamental Design for a Dial Plate, of which the following is a specification, reference being had to the accompanying drawing, forming part thereof, in which—

Figure 1 is a face view of a dial plate showing my new design.

Figure 2 is an edge view of the same.

Figure 3 is an edge view looking from a point at right angles to that of Fig. 2.

I claim:

The ornamental design for a dial plate as shown.

MARCUS H. RHODES.
